UNITED STATES PATENT OFFICE.

CHRISTOPHER STEELE SPOFFORD, OF STURGIS, MICHIGAN, ASSIGNOR TO STURGIS
STEEL GO-CART COMPANY, OF STURGIS, MICHIGAN.

COLLAPSIBLE CARRIAGE.

1,125,756.

Specification of Letters Patent. Patented Jan. 19, 1915.

Application filed October 4, 1910. Serial No. 585,244.

To all whom it may concern:

Be it known that I, CHRISTOPHER STEELE SPOFFORD, a citizen of the United States, residing at Sturgis, Michigan, have invented certain new and useful Improvements in Collapsible Carriages, of which the following is a specification.

This invention relates to improvements in collapsible carriages.

10 The main object of this invention is to provide in a collapsible carriage an improved spring seat and spring seat back structure.

15 Further objects, and objects relating to structural details, will definitely appear from the detailed description to follow.

I accomplish the objects of my invention by the devices and means described in the following specification.

20 The invention is clearly defined and pointed out in the claims.

A structure which is a preferred embodiment of my invention, is clearly illustrated in the accompanying drawing, forming a 25 part of this specification, in which:

Figure I is a side elevation of a structure embodying the features of my invention, a portion of the handle being broken away. Fig. II is a rear elevation, a portion of the 30 handle and a portion of one of the rear wheels being broken away. Fig. III is an inverted detail of the seat, showing the arrangement of the springs thereon. Fig. IV is a side elevation of my improved seat, in 35 its collapsed position. Fig. V is a detail vertical section taken on a line corresponding to line 5-5 of Fig. II, looking in the direction of the little arrows at the ends of the section lines.

40 In the drawings, similar numerals of reference refer to similar parts throughout the several views.

Referring to the drawing, 1 represents the running-gear frame, which, in the structure illustrated, is formed of tubing bent into a U-shape. The handle 2 is pivotally secured to the rear end of the frame, at 3. On each side of the side bars of the running-gear frame are clip-like hangers 4 for the wheel 45 supports 5. These wheel supports have downwardly projecting arms 6 at each end, terminating in spindles for the wheels 7. A pair of levers 8 are pivoted on the running-gear frame at 9, with their lower ends 50 projecting below the running-gear frame to

engage the cam members 10 on the wheel supports 5. These levers 8 are connected to the handle 2 by the side bars 11, the side bars being pivoted to the handles at 12, and to the upper ends of the levers by the pivots 60 13. The cam members are not described in detail, as they form no part of this invention.

The wheel supports are braced and the levers 8 locked in their erected position, 65 thereby locking the carriage in its erected position by a device comprising the brace 14, which is pivoted at 15 on the running-gear frame, the upper end of the brace being extended rearwardly beyond the pivot, and 70 the link 16, which is pivoted to one of the levers 8 and to the upper end of the brace. On the wheel supports are forked clips 17, adapted to receive the braces when the parts are erected. A lever 18 is pivoted at 18' on 75 one of the brace members for releasing the lock and disengaging the brace. The details of this mechanism are not further described herein, as they form the subject-matter of my application for patent filed concurrently 80 herewith. The forward ends of the wheel supports are also braced by the braces 19, which are pivoted on the running-gear frame and connected by the links 20 to the levers 8. The foot rest 21 is not described 85 in detail herein as it forms no part of my present invention.

The seat 22 is supported by the S-shaped rear springs 23, one arm of each spring being secured to the seat and the other to the cross piece 30 on the running-gear frame. The forward end of the seat is supported by downwardly and forwardly-projecting arms 24, which are in the form of blade-springs 90 having a quarter twist therein, as shown at 95 25, the horizontally-disposed portions of the springs being secured to the bottom of the seat, as by means of the screws 26, while the vertically-disposed portions of the springs are secured to the frame by means of the horizontally-disposed pivots 27. These front 100 supporting members 24 are preferably arranged to diverge forwardly, as illustrated, so that they effectively brace and support the seat against lateral movement.

To limit the rebound of the springs, and prevent their being overstrained or distorted by an undue strain, such as might result if the back were forcibly retained in its erected position when the automatic back collapsing 110

is present, as shown, I provide a pair of rods 28, which are preferably of wire, having eyes at their upper ends for the screws 29, their lower ends being arranged through 5 holes provided therefor in the cross piece 30, the ends of the rods being turned laterally at 31. The back 32 is mounted on the seat and adapted to be swung forwardly thereon, as shown in Fig. V when the structure 10 is collapsed. This is done automatically, but as the mechanism by which it is accomplished forms no part of this invention, I do not describe the same herein. The back is adjustably mounted, as indicated by 15 the dotted lines in Fig. I, so that it may be adjusted to a reclining position. When it is adjusted to this position, the weight of the child reclining in the carriage is thrown well to the rear. By this arrangement of 20 spring described, the springs are very resilient, and are adapted for different weights, being sufficiently resilient for light weights, and, at the same time, capable of carrying heavier weights effectively. An 25 other advantage is that the springs are substantially noiseless. Further, the particular form of springs coact very effectively,—that is, the S-springs are not injuriously distorted by the downward and upward movements 30 of the seat, in which the seat is moved backwardly and forwardly to a limited degree. Further, the seat is effectively supported so that it has practically no lateral movement. The seat is not affected by the 35 collapsing of the carriage otherwise than the collapsing of the back, as the handles swing down at the sides of the seat, as shown in Fig. IV.

I have illustrated and described my improvements in detail in the form in which 40 I have embodied them in practice. I am aware, however, that my invention is capable of very great variations in structural details without departing from my invention, and I desire to be understood as claiming the same specifically, as illustrated, as well as broadly within the scope of the appended claims.

Having thus described my invention, what 50 I claim as new and desire to secure by Letters Patent is:

1. In a folding carriage, the combination with the running-gear frame, comprising side pieces and a cross piece, of collapsible 55 wheel supports; means for collapsing and erecting said wheel supports; a seat; S-shaped rear springs for said seat, one arm of each spring being secured to said cross piece and the other to said seat; substantially straight blade-like front springs secured to said seat to project downwardly and forwardly therefrom, said front springs having quarter twists therein, the upper 60 horizontally-disposed portions of said springs being rigidly secured to said seat 65

and the lower vertically-disposed portions being secured by horizontally-disposed pivots to the side pieces of said running-gear frame; a pair of stop rods secured to said seat to project downwardly and rearwardly 70 through said cross piece in proximity to said rear springs; and a handle pivoted to the rear ends of said frame side pieces and adapted to fold down at the side of said seat when the frame is collapsed, said seat being 75 supported independently of said handle and said wheel support actuating means, said wheel support actuating means being operatively connected to said handle.

2. In a folding carriage, the combination 80 with the running-gear frame, comprising side pieces and a cross piece, of collapsible wheel supports; means for collapsing and erecting said wheel supports; a seat; S-shaped rear springs for said seat, one arm 85 of each spring being secured to said cross piece and the other to said seat; substantially straight blade-like front springs secured to said seat to project downwardly and forwardly therefrom, said front springs 90 having quarter twists therein, the upper horizontally-disposed portions of said springs being rigidly secured to said seat and the lower vertically-disposed portions being secured by horizontally-disposed pivots to the side pieces of said running-gear frame; and a handle pivoted to the rear ends of said frame side pieces and adapted to fold down at the side of said seat when the frame is collapsed, said seat being supported independently of said handle and said wheel support actuating means, said wheel support actuating means being operatively 95 connected to said handle.

3. The combination with the running-gear 105 frame, of a seat; S-shaped rear springs for said seat, one arm of each spring being connected to said frame and the other to said seat; substantially straight blade-like front springs secured to said seat to project downwardly and forwardly therefrom, said front springs having quarter twists therein, the upper horizontally-disposed portions of said 110 springs being rigidly secured to said seat and the lower vertically-disposed portions 115 being secured by horizontally-disposed pivots to the side pieces of said running-gear frame.

4. The combination with the running-gear 120 frame, of a seat; S-shaped rear springs for said seat, one arm of each spring being connected to said frame and the other to said seat; substantially straight front supporting springs secured to said seat to project forwardly therefrom, the rear ends of said 125 springs being secured to said seat and their forward ends to said running gear frame; and a rod secured to said seat to project obliquely downwardly and rearwardly and 130 slidably engage said running-gear frame.

5. The combination with the running-gear frame, of a seat; rear springs for said seat; and substantially straight supporting arms of spring material secured to said seat to project downwardly and forwardly therefrom, said arms being blade-like in form, having quarter twists therein, the upper horizontally-disposed portions of the arms being rigidly secured to said seat and the lower vertically-disposed portions thereof being secured by horizontally-disposed pivots to said running-gear frame.

6. The combination with the running-gear frame, of a seat; S-shaped rear springs for

said seat; and substantially straight forwardly-projecting supporting arms of spring material for the forward end of said seat, the rear ends of said springs being secured to said seat, their forward ends being secured to said running-gear frame, all co-acting for the purpose specified.

In witness whereof, I have hereunto set my hand and seal in the presence of two witnesses.

CHRISTOPHER STEELE SPOFFORD. [L. S.]
